The ornamental design for a lid for a roll out trash cart, as shown and described.

DESCRIPTION

FIG. 1 is a perspective view of the new design; FIG. 2 is a left side elevational view of the design of FIG. 1, the right side being a mirror image thereof; FIG. 3 is a front elevational view of the design of FIG. 1; FIG. 4 is a rear elevational view of the design of FIG. 1; FIG. 5 is a bottom plan view of the design of FIG. 1; and, FIG. 6 is a top plan view of the design of FIG. 1.

The broken line showing of a trash cart is for illustrative purposes only and forms no part of the claimed design.
